COAT AND TROUSER HANGER

Jack M. Dinken, New York, N. Y.

Application September 20, 1945, Serial No. 617,472

6 Claims. (Cl. 223—91)

1

This invention relates to a device which is designed and adapted to hang a coat type of garment together with trousers, slacks, or other articles.

An object of the invention is the provision of a hanger of the indicated character which may be used advantageously to support a coat and trousers in such manner that the shape of the coats is preserved and air may circulate inside of the coat and through the material thereof.

A further object is the provision of a garment hanger embodying improvements whereby a garment is kept from slipping off the hanger.

A further object is the provision of a garment hanger embodying novel features of construction by virtue of which the hanger is sturdy and efficient for the intended purposes.

The nature of the invention and its distinguishing features and advantages will appear when the following specification is read in conjunction with the accompanying drawings, in which:

Figure 1 is a front view of a garment hanger embodying the features of the present invention.

Figure 2 is a top view.

Figure 3 is a back view.

Figure 4 is an end view.

Figure 5 is an enlarged sectional view taken on the line 5—5 of Figure 1.

Referring more particularly to the drawings it will be apparent the hanger includes a main part 10 which is constructed to support a coat type of garment. The part 10, structurally, is of one piece, and is of such form that it may be molded of suitable plastic material. Said part 10 consists of a back section 11 merging into a top section 12. The section 11 is curved from one side to the other side, or in other words it is arcuate lengthwise. The lower edge of the section 11 is scalloped in the present instance, but any other shape or contour may be adopted.

The top section 12 is curved forwardly and extends downwardly in front of the section 11 part way of the latter. Said section 12 slopes at opposite sides of the vertical axis of the part 10, and conforms generally to the shoulder and collar portions of the conventional coat type of garment.

In the back section 11 there are holes 13 for the passage of air through the material of a garment supported on the part 10.

In order to support a second garment, such as trousers, slacks and any other article, there is provided a supporting member in the form of a rod 14, which is secured at the ends to the

2

main part 10 transversely of the vertical axis thereof.

The hanger has a suspension member in the form of a hook 15, which is secured to the top section 12. The hook 15 may be engaged over a rod or other support in a clothes closet for obvious purposes.

In order to prevent a garment supported on the rod 14 from slipping off, there is provided a clamping member 16 complementary to the rod 14. The member 16 has a tubular shank 17 which telescopically receives a tubular portion 18 of the hook 15, and is thus mounted on the part 18. Suitable spring pressed detents 19 are secured to the portion 18 in registry with holes 20 respectively in said portion 18. The shank 17 has indentations 21 therein providing cam surfaces which cooperate with the detents 19. A helical spring 22 is arranged in the shank 17 with one end bearing on the hook portion 18 and the other end bearing on the clamping member 16.

The provision and arrangement are such that the clamping member 16 is movable between a clamping position and an unclamping position. The member 16 is releasably held in its unclamping position by the detents 19 engaged in the indentations 21. This is accomplished by merely sliding the clamping member 16 upwardly until the detents 19 engage themselves in the indentations 21. By exerting a downward pull on the member 16 the detents become disengaged from the indentations 21, there being a camming action of the surfaces of said indentations. The down pull on the member 16 causes the sloping sides of the recesses or indentations 21 to force the ball-shaped detents inward, and as soon as the detents are out of line with the indentations 21 the member 16 is free to move downward. This is supplemented by the action of the spring 22 which forces the member 16 into its clamping position with respect to the rod 14, and thereby clamping a garment, such as trousers, hung on the rod 14. In this manner the trousers are kept from slipping off the rod. If desired, both the rod 14 and the member 16 may be roughened, as at 23, to prevent the garment from slipping from the rod 14.

The construction of the main part 10, and the arrangement of the rod 14 and clamping means enable a coat together with trousers to be suspended in such manner that the shape of the coat will be preserved, and air may circulate inside of the coat and through the material of the coat.

Having thus described my invention, what I claim as new and desire to secure by Letters Patent, is:

1. A garment hanger having a transverse garment supporting member, a movable clamping member adjacent the supporting member to cooperate with the supporting member to retain the garment on the supporting member, the hanger carrying a part on which said clamping member is mounted, and detent means on said part to hold the clamping member in a clamping position or in an unclamping position with respect to said supporting member, said clamping member having slidable engagement with said part to hold the garment or release same.

2. In a garment hanger, two garment supporting members connected with each other, a clamping member, means on one of the supporting members for mounting the clamping member for sliding movement thereon between a clamping position and an unclamping position with respect to the other of said supporting members, and detent means on said mounting means to hold the clamping member in clamping position to retain a garment on the other supporting member or to retain the clamping member in its unclamping position.

3. In a garment hanger, a main part bearing a garment supporting member, a suspension member on the main part for the hanger, a clamping member received by said suspension member for up and down sliding movement between a clamping position and an unclamping position with respect to said supporting member, resilient means on said suspension member to move the clamping member into its clamping position on the supporting member, and means on said suspension member to releasably retain the clamping member in its clamping position to retain a garment on the supporting member, or to retain the clamping member in its unclamping position.

4. In a garment hanger as set forth in claim 3, wherein said last means consists of detents on said suspension member and indentations on said clamping member which coact with said detents.

5. A garment hanger comprising a main part, a transverse suspension rod supported at its ends by said main part, a hook attached to the main part of the hanger, said hook having a portion which extends towards said rod, a clamping member having telescopic engagement with said portion, a spring engaging said clamping member and said portion to urge the clamping member towards the suspension rod, and releasable means associated with said portion and said clamping member to cooperate with said spring to retain said member in operative position with respect to said rod, or hold said member out of operative position.
